UNITED STATES PATENT OFFICE.

JULIUS A. DUMBIER, OF NANTICOKE, PENNSYLVANIA.

BOLT.

1,018,887.

Specification of Letters Patent.

Patented Feb. 27, 1912.

Application filed January 8, 1912. Serial No. 670,043.

To all whom it may concern:

Be it known that I, JULIUS A. DUMBIER, a subject of the King of Hungary, and resident of Nanticoke, county of Luzerne, State of Pennsylvania, have invented certain new and useful Improvements in Bolts, of which the following is a specification.

This invention relates to locking devices and more particularly to fastening means for doors of barns, sheds and similar outside buildings. However the device may be applied to any door, gate, window or like structure.

The invention has for one of its objects, 15 to make a bolt which cannot be pulled straight out of the keeper and which can not be readily opened by any one not familiar with the combination of the device.

Another object is to produce a simple and 20 inexpensive device having few parts, which are durable and not apt to get out of order.

Other objects and novel features of the invention will be apparent from the following description taken in connection with the 25 drawings, in which,

Figure 1 is a perspective view of the device applied to a door showing the same unlocked; Fig. 2 is a horizontal plan view showing the bolt in its extreme and locked 30 position in the keeper; Fig. 3 is a sectional view along the line 3—3 of Fig. 4, with the top member of the keeper removed and turned up; Fig. 4 is a sectional view along the line 4—4 of Fig. 1 looking in the direction of the arrows showing the bolt in position; Fig. 5 is a sectional view along the line 35 5—5 of Fig. 4 looking in the direction of the arrows, the bolt being removed.

Referring to the drawings I provide two 40 members, one of which may be secured to the door 8 and one to the door casing 9 or they may be applied to two hinged doors. One of the said members constitutes a guiding device for the bolt and the other constitutes the keeper. The guiding device 45 consists of a base 10 adapted to be secured to either the door 8 or the casing 9 by means of screw fastening means 11. The base 10 is provided with two upstanding parallel ears 50 12, each of which has a slot 13 adapted to receive the bolt 14. The bolt 14 consists of a single circular bar of metal and is bent at right angles at the end and squared off to form a projection or tongue 15 which engages in the keeper to lock the two members 55 together. The bolt 14 is also provided with

a knob or thumb piece 16 which is preferably provided with a screw threaded extremity whereby it may be removed so that the bolt may be taken out of the guides or 60 ears 12. The knob 16 is secured to the bolt 14 at a sufficient distance from the projection 15 to permit the latter to move to its extreme position in the keeper. The knob 16 also constitutes a stop for the bolt 14 when 65 sliding backwardly and forwardly in the ears 12. It is to be understood that the bolt 14 is of sufficient length to be at all times held by the guide members 12.

The keeper consists preferably of two independent members 17 and 18 inclosed within a casing which latter is provided with a keyway 20' adapted to receive the tongue 15 and bolt 14. The casing is preferably of 70 a single piece of metal or a single casting, 75 as is clearly shown in Fig. 4, and consists of a base portion 20 and an outwardly overhanging portion 21. The base portion 20, a part of which constitutes one side wall of the casing, is provided with bolt holes 22, 80 whereby the casing may be secured to a building or other structure by any suitable fastening means, as the screws 23. The overhanging portion 21 constitutes the top and other side wall of the casing and is provided 85 to exclude moisture from the interior of the same.

In assembling the keeper the member 17 is first positioned in the casing with its smooth side abutting against the inner top 90 wall thereof and the member 18 which constitutes the bottom wall of the casing is then secured against the member 17 by means of the screws 19, rivets or any similar fastening means. It will be noticed that the 95 members are designed to be assembled before securing the casing to the building and the heads of the screws 19 being on the inside, will be inaccessible to any person unauthorized to take the keeper to pieces. 100

While the casing and member 17 are shown as two separate elements, it is to be understood that the two may be cast in a single piece but I prefer to use the construction as shown because it is then possible to utilize different combinations with the same casing.

The combination in the keeper is effected by providing members 17 and 18 with various recesses which correspond in some 105 places and in others are quite unlike one another. To accommodate the body of the 110

- bolt 14 a central passageway 24 is provided in the member 18 and leading therefrom are other recesses which, coöperating with the recesses in the member 17, constitute an independent tortuous or irregular passageway surrounding the passageway 24. This irregular passageway is of sufficient width and depth to receive the projection or tongue 15 therein and the latter is adapted to engage any one of the shoulders formed by the walls of the recesses leading from the passageway 24 and is thereby locked at various points in its projected or partly retracted position.
- 15 The operation of the device will be clear from the foregoing description. The bolt may be opened by one who is familiar with the combination by simply turning the bolt 14 by means of the knob or thumb piece 16 and at the same time retracting or projecting the same, whereby the tongue 15 will move through the tortuous passageway past the projections forming the same said passageway.
- 20 It will be understood that the details of the combination may be varied and that therefore I do not wish to be limited to the precise details as shown.
- 25 What I claim as new and desire to secure by Letters-Patent is,
- 30 1. In a device of the class described, the combination of a bolt having a projection thereon, a keeper having a longitudinal passageway in which the body of the bolt may be moved, and an irregular passageway surrounding the longitudinal passageway adapted to receive the projection of the bolt, means for concealing said projection
- and passage-ways from view when in operative relation, and means coöperating with the projection to lock the bolt in the keeper.
2. In a device of the class described, the combination of a keeper comprising coöperating members, one of said members having a longitudinal passageway provided with recesses in the walls thereof, another member fitting against the first named member and provided with recesses to coöperate with the recesses in the first mentioned member to form a tortuous passageway surrounding said longitudinal passageway, a bolt provided with a tongue and adapted to be projected into the keeper, said tongue adapted to engage the walls of the recesses to lock the bolt in the keeper.
3. In a device of the class described, a door casing and a door, a bolt provided with a tongue adapted to slide laterally on the door, a keeper on the casing to receive the bolt, said keeper having a longitudinal passageway and a tortuous passageway, the passageways communicating one with the other, means for concealing said passageways from view, the body of the bolt adapted to reciprocate in the longitudinal passageway and the tongue on said bolt movable in said tortuous passageway and means coöperating with the tongue to lock the bolt in the keeper.
- 35 In testimony whereof I affix my signature in presence of two witnesses.
- JULIUS A. DUMBIER.
